MARINE TANKER

Robert Henry Brown, Worting, near Basingstoke, England, assignor to Wm. Cory & Son Limited, London, England

Filed Apr. 1, 1958, Ser. No. 725,673

Claims priority, application Great Britain Apr. 5, 1957
9 Claims. (Cl. 114—74)

This invention relates to water-borne tankers, particularly ocean-going tankers, for the transport in liquid form, at low temperature and approximately atmospheric pressure, of substances which are normally in a gaseous state. The gas which comes mainly into question is methane, but the references herein to methane are, wherever the context allows, to be read as references also to like gases which it may be desirable to transport in the liquid state.

Liquid methane can be carried in heavily-insulated tanks made of aluminum magnesium alloy, this material being chosen for its good welding properties and because its mechanical properties are not adversely affected by subjection to the temperature of liquid methane, i.e. approximately minus 260° Fahrenheit (minus 162° centigrade). Should a leak develop in a tank, the liquid methane will rapidly find its way through the insulation unless very special precautions are taken to prevent it. It is of the utmost importance that a leak should be stopped at the earliest possible moment because at the temperature of liquid methane the mechanical properties of steel deteriorate alarmingly. Were the liquid methane to come into contact with the ship's plates, the ship would no longer be structurally safe. Furthermore, the escaping liquid would rapidly evaporate and give rise to a dangerous concentration in the hold space of methane gas which, in the presence of air, might easily explode.

It is an object of the invention to provide rapidly effective emergency means for stopping leaks from the methane tanks.

According to the present invention, there is provided a marine tanker for the bulk transport in the liquid state at low temperature of methane (or like ordinarily-gaseous substance), wherein each cargo tank is disposed within a watertight hold compartment, and means are provided for rapidly flooding the space within the hold compartment around the tank with water, or other liquid such as oil, which will freeze at a temperature much above the liquefaction temperature of methane.

When on the occurrence of a leak, the space around the tank in its hold compartment is flooded, the liquid in that space is rapidly frozen by the escaping methane and effectively plugs the leak, and keeps the tank in a safe condition until a permanent repair can be effected.

The above and other features of the invention will be apparent in the following description, given by way of example, of one embodiment in accordance with the invention, reference being had to the accompanying drawings in which:

FIGURE 1 shows in elevation a marine tanker for the transport of methane,

FIGURE 2 is a plan showing the arrangement of the methane tanks in the holds,

FIGURE 3 is a further plan showing the arrangement of tanks at main deck level, and

FIGURE 4 is a diagram of the layout of the hold-flooding piping connections, and

FIGURES 5 and 6 are transverse sections taken on the lines 5—5 and 6—6 of FIGURE 2 respectively.

Referring firstly to FIGURES 1 and 2, the cargo-carrying section of the tanker hull 10 is divided into six separate main hold compartments 11 to 16 by a series of

2

transverse bulkheads 17. Disposed individually in the hold compartments 11 to 16, in a closely-spaced row along the fore-and-aft centre line of the vessel are six main cargo tanks 18 to 23 bearing heavy insulation 180 (FIGURE 5). These main tanks are, for the most part, substantially cylindrical in form with their principal axes vertical, and in general they extend at their widest parts for substantially the whole width of the vessel although tanks 19 and 23 are somewhat less in diameter than tanks 20, 21 and 22, and the most forward tank 18 is a good deal less still in diameter.

The vessel is of turret construction, that is to say it has a main deck at the level 24 and a narrower turret deck above at the level 25. Each of the main tanks 18 to 23 extends up through the main deck at level 24, and, with the exception of the tank 20, the portions of the tanks that protrude above the main deck are as large in diameter as can be conveniently accommodated within the turret structure 26. To this end, tanks 19, 21, 22 and 23 have stepped-in upper portions 28, 29 30 and 31, but the forward tank 18, being already relatively narrow, does not need to be stepped-in. Each of the six tanks terminates at its upper end in a narrow neck 27 surmounted by a pump motor housing 32. In the case of the five tanks 18, 19, 21, 22 and 23 the narrow tank neck 27 reaches up through the turret deck at level 25 and the housing 32 is situated on said deck, but the tank 20, for reasons which need not be discussed here, is not as high as the other five, having its neck 27 terminating only just above the main deck level 24 and its pump motor housing 32 disposed on the main deck within the turret structure.

Owing to the circular plan form of the main tanks 18 to 23, there is an appreciable space below decks between one tank and the next at opposite sides of the vessel, and in the case of tanks 19 to 23 these spaces between are utilised by disposing in them eight additional wing tanks 33 of much smaller capacity and bearing insulation 181 (FIGURE 6). The wing tanks 33 are all cylindrical with their principal axes upright, and are located wholly below the main deck level 24. As will be seen in FIGURE 2, the arrangement of bulkheads between the main tanks 19 to 23 is such that each wing tank 33 has its own individual water-tight hold compartment 34, each of the bulkheads 17 branching, as it were, into two diverging bulkheads 35 to embrace a wing tank as it approaches each side of the hull.

It will be observed that each of the small wing tanks 33 has a diameter only about one-fifth the beam of the ship, and, as can be seen in FIGURE 3, the turret structure 26 and turret deck 25 have a width which is about 60% of the ship's beam. In a typical example of a 16,600 ton dead-weight methane tanker, the largest main cargo tanks might have a capacity of the order of 280,000 cubic feet, and the wing tanks a capacity of 9,000 cubic feet each. In a vessel of this order of size the turret width of approximately 60% of the beam affords a working deck on either side that is wide enough for easy working.

As can best be seen in FIGURE 3, the spaces within the turret structure 26 and between the portions of the main cargo tanks lying therein, are occupied by a cargo liquefaction plant shown in block form at 182 and by tanks 80 on the main deck. Thus there are tanks 80 between the pairs of main tanks 18 and 19, 21 and 22, and 22 and 23, with an additional smaller tank beyond the aft methane cargo tank 23, while between the methane cargo tanks 19 and 21 and over the methane cargo tank 20 there is a further large tank 80 and a compartment 81 occupied by cargo liquefaction plant shown in block form at 183. Despite the heavy insulation of the methane cargo tanks, there will be a certain amount of

methane boiling off in them during a voyage, and the primary purpose of the liquefaction plant is to re-liquefy excess gaseous methane drawn off from the tanks so that it can be returned to the tanks and the liquid level kept up. Each main tank 18 to 23 is normally kept topped up so that the liquid level is in the comparatively narrow neck 27, whereby both the free liquid surface area for evaporation, and the liquid-free volume, in each tank are kept as low as possible.

The deck tanks 80 will contain oil cargo or water ballast, and their position high up in the ship enables these tanks to be used to control stability so that the ship will have an easy motion in rough seas. The deck tanks 80 can also be employed as described hereinafter, for flooding the hold space around a methane cargo tank in the event of the tank springing a leak, whereupon the oil or water ballast flooding the hold will freeze around the leak and stop it. The deck tanks 80 are simply constructed of welded plate, and are rectilinearly-shaped as shown in FIGURE 3, being multi-sided so as to best fill the available spaces, and each with a centreline division.

In addition to the methane cargo tanks, and the deck tanks 80, the vessel has, besides further conventional ballast which will not be described in detail, a number of deep tanks 82, 83. The deep tanks 82 are in the fore part of the ship, grouped around the fore-most methane tank 18, while the tanks 83 are grouped around the aft methane tank 23. The deep tanks 82, 83 may be filled with water ballast, but preferably they are used for the transport of an oil cargo, in addition to the liquid methane cargo. In a ship of about 16,600 tons dead-weight these tanks together with the deck tanks can carry about 9,300 tons of oil cargo, which is a valuable supplement to the liquid methane cargo.

The individual hold compartments 11 to 16 and 34 are all liquid-tight, and all the deck tanks 80 can be connected to flood the space around any one of the cargo tanks. Owing to the location of the deck tanks the flooding can be carried out rapidly under gravity, so that this emergency provision is not dependent on the functioning of pumping machinery. The largest of the individual cofferdam compartments, in a tanker of about 16,600 tons methane dead-weight, is of the order of 120,000 cubic feet, and the total capacity of all the deck tanks approximately 130,000 cubic feet, so that there is enough liquid in the deck tanks to fill individual cofferdam spaces. The deck tanks 80 are connected for filling to the ballast and oil cargo lines and pump installations of the vessel.

As shown in FIGURE 4, each of the deck tanks 80 is connected by branch pipes 150, which include hand-operated valves 151, to a water ballast ring main 152 running along the turret, and also by branch pipes 160, including hand-operated valves 161, to an oil cargo line 162. The deck tanks are also linked to one another by communicating trunks 170. Further branch pipes 153, also provided with hand-operated valves 154, lead from the deck tanks 80 to each of the cofferdam spaces 11 to 16 and 34 surrounding the methane tanks 18 to 23 and 33. By this means all the water or oil tanks 80 can be connected to any given hold compartment in the event of a leak of methane, and the tanks 80 can be recharged through either the ballast main 152 or the oil cargo line 162. The oil line 162 has provision for shore connections via cargo oil pumps 171, while the ballast main is connected to sea lines via ballast pumps 172. During flooding, air escapes from the holds through gas-freeing lines 173, which lead to mast vents (not shown).

I claim:

1. In a marine tanker for the bulk transport of liquefied gas at low temperature, the combination of a hull, a main deck, a plurality of transverse liquid-tight bulkheads dividing up the cargo space below the main deck into a plurality of separate main hold compartments, a plurality of heavily-insulated main tanks for liquefied

gas cargo, said tanks being disposed in a closely-spaced row one in each of the hold compartments, a plurality of deck tanks disposed on the main deck, a ring main, connections from each of the deck tanks to the ring main, connections from the ring main to the space around the cargo tank in each of the hold compartments and valve means in said connections operable to enable liquid in the deck tanks to be discharged into any one selected hold compartment.

10 2. In a marine tanker for the bulk transport of liquid methane at low temperature, the combination of a hull, a main deck, a plurality of liquid-tight bulkheads dividing up the cargo space below the main deck into a plurality of separate main hold compartments, a plurality of heavily-insulated tanks for liquid methane cargo, said tanks being disposed one in each of the hold compartments, a plurality of storage tanks for hold-flooding liquid disposed at a level substantially above the level of the cargo tanks, hold-flooding connections from all the storage tanks to all the spaces around the cargo tanks in the hold compartments and valve means in said connections operable to enable the liquid in the storage tanks to be discharged under gravity into any of the hold compartments.

25 3. In a marine tanker for the bulk transport of liquid methane at low temperature, the combination of a hull, a main deck, a plurality of transverse liquid-tight bulkheads dividing up the cargo space below the main deck into a plurality of separate hold compartments, a plurality of heavily-insulated tanks for liquid methane cargo said tanks being disposed one in each of the hold compartments, a plurality of deck tanks for hold-flooding liquid disposed on the main deck, a hold-flooding liquid line, connections from each of the deck tanks to said liquid line, connections from said liquid line to the space around the cargo tank in each of the hold compartments and valve means in said connections operable to enable liquid in all the deck tanks to be discharged under gravity into any one selected hold compartment.

40 4. A tanker as claimed in claim 3, wherein the deck tanks are connected to a ship's ballast system and oil cargo system so that the deck tanks can be charged when required.

5. A tanker as claimed in claim 3, said heavily-insulated tanks comprising a plurality of main cargo tanks arranged in a closely-spaced row along the fore-and-aft center line of the vessel each tank extending at its widest part across substantially the full width of the vessel, and wherein at least some of the tanks have portions of reduced cross-section projecting up through the main deck and enclosed within a turret structure narrower than and above said deck, and at least some of the deck tanks are disposed in the turret between said portions of the cargo tanks.

6. A tanker as claimed in claim 5, wherein smaller wing cargo tanks are located wholly below the main deck and on opposite sides of the hull in spaces between the main cargo tanks, and the main and wing cargo tanks are all installed in individual hold compartments having flooding connections from the deck tanks.

7. In a marine tanker for the bulk transport of liquefied natural gas at low temperature, the combination of a hull, a main deck, a plurality of transverse bulkheads dividing up the cargo space below the main deck into a plurality of separate main hold compartments, a plurality of heavily-insulated main tanks for liquefied gas cargo said tanks being disposed in a closely-spaced row one in each of the hold compartments with upright axes intersecting the fore and aft center line of the vessel, a plurality of smaller heavily-insulated wing tanks for liquefied gas cargo, said wing tanks being disposed in wing spaces between the main tanks towards the sides of the ship and said transverse bulkheads being formed around said wing tanks to enclose each wing tank in its own separate wing hold compartment, storage for hold-flooding liquid disposed at substantially main deck level, a

75

hold-flooding line, connections from said liquid storage to the hold-flooding line, connections from the hold-flooding line to the space around the cargo tank in each of the hold compartments and valve means in said connections operable to enable liquid in said liquid storage to be discharged into the hold compartment.

8. In a marine tanker for the bulk transport of liquid methane at low temperature, the combination of a hull, a main deck, a plurality of transverse bulkheads dividing up the cargo space below the main deck into a plurality of separate hold compartments, a turret deck narrower than the main deck and extending fore-and-aft above the main deck over said hold compartments, a plurality of heavily-insulated tanks for liquid methane cargo each having a configuration that is mainly of upright cylindrical form, said tanks being disposed in a row one in each of the hold compartments with their upright axes intersecting the fore-and-aft center line of the vessel and each tank being stepped in at at least one level near the top thereof so as to give the tank a centrally-placed narrow neck portion with the full-diameter portion of the tank disposed wholly below the main deck and the neck portion projecting above the main deck and lying within the confines of the portion of the deck width defined by the turret deck, at least some of said tanks having between the neck and the full-diameter portion a stepped section of an intermediate diameter which intermediate diameter stepped section commences just below the main deck but is otherwise located between the turret deck and the main deck and is of a diameter as large as the width of the turret deck will allow, a plurality of deck tanks disposed on the main deck underneath the turret deck and between the intermediate diameter sections of the cargo tanks, hold-flooding liquid line connections from all the deck tanks to all the spaces around the cargo tanks in the hold compartments and valve means in said connections operable to enable liquid in all the deck tanks to be discharged into any one selected hold compartment.

9. In a marine tanker for the bulk transport of liquid methane at low temperature, the combination of a hull, a main deck, a plurality of transverse liquid-tight bulkheads dividing up the cargo space below the main deck into a plurality of separate main hold compartments, a turret deck narrower than the main deck and extending fore-and-aft above the main deck in uninterrupted manner over all said hold compartments, turret side structure enclosing the space between the main and turret decks, a plurality of heavily-insulated main tanks for liquid methane cargo each having a configuration that is mainly

of upright cylindrical form and occupies at its widest part substantially the whole available width of the vessel, said tanks being disposed in a closely-spaced row one in each of the hold compartments with their upright axes intersecting the fore-and-aft centre line of the vessel and each tank being stepped in at at least one level near the top thereof so as to give the tank a centrally-placed narrow neck portion with the full-diameter portion of the tank disposed wholly below the main deck and the neck portion projecting above the main deck and lying within the confines of the portion of the deck width defined by the turret structure, at least some of said tanks having between the neck and the full-diameter portion a stepped section of an intermediate diameter which intermediate diameter stepped section commences just below the main deck but is otherwise wholly located within the turret structure and of a diameter as large as the enclosed space within the turret structure will allow, those tanks with such an intermediate diameter section having their narrow neck portions projecting up above the level of the turret deck, a plurality of smaller heavily-insulated wing tanks for liquid methane cargo each having a substantially upright cylindrical configuration, said wing tanks being disposed wholly below the main deck in the wing spaces between the main tanks towards the sides of the ship and said transverse bulkheads being formed around said wing tanks to enclose each wing tank in its own separate wing hold compartment, a plurality of deck tanks disposed on the main deck within the turret structure and between the intermediate diameter sections of the main cargo tanks, a ring main, connections from each of the deck tanks to the ring main, connections from the ring main to the space around the cargo tank in each of the hold compartments and valve means in said connections operable to enable liquid in all the deck tanks to be discharged into any one selected hold compartment.
